[57] CLAIM

The ornamental design for a carton for food products, as shown and described.

DESCRIPTION

FIG. 1 is a perspective view of a carton for food products showing my new design;

FIG. 2 is a front elevational view thereof;

FIG. 3 is a top plan view thereof;

FIG. 4 is a side elevational view thereof, taken from the right-hand side of FIG. 2, the left-hand side view being a mirror image;

FIG. 5 is a rear elevational view thereof; and,

FIG. 6 is a bottom plan view thereof.

The broken line showing on FIGS. 1 and 2 represent tear lines.
